CATHODE BEAM TUBE AND CIRCUIT
THEREFORRichard L. Snyder, Jr., Princeton, N. J., assignor
to Radio Corporation of America, a corporation
of Delaware

Application June 20, 1945, Serial No. 600,498

7 Claims. (Cl. 315—12)

1

There are various uses for cathode beam tubes capable of storing received signals, such as in radars, frequency reducers and other devices.

An object of the invention is to provide a cathode beam tube and circuit that will store signals for a predetermined number of scanning cycles on a dielectric target before utilization thereof.

Another object is to provide a cathode beam tube in which signals are stored on a dielectric target during one scanning cycle and utilized in the next.

Another object is to provide a cathode beam tube in which signals are recorded on a dielectric target during one scansion by the beam and discharged therefrom on the next scansion by varying the relative potentials of screens positioned adjacent the target.

Other objects will appear in the following description, reference being had to the drawing, in which:

The single figure of the drawing is a diagrammatic illustration of my storage tube and circuits therefor.

Referring to the drawings, the storage tube 1 of my invention has an evacuated envelope 2 surrounded by a coil 3 for magnetic focusing of the electrons. Storage tube 1 has a cathode 4 with heater 5, surrounded by control grid 6 having the usual orifice for controlling the cathode beam 7. In front of the grid is the cylindrical anode 8 having an apertured wall 8a for passage of the beam 7. The target 9 is secured by any means at the front end of the envelope 2. This target may be round, square, or any other desired shape. It preferably consists of a thin sheet of mica, though other dielectric materials may be used. A signal plate 10 is positioned against the side of the target remote from the gun. On the gun side is positioned a shield screen 11 spaced a few millimeters therefrom. This is joined to wall coating 12, which is connected to cylindrical anode 8. Closely adjacent the screen 11 on the gun side is placed control screen 13. Screens 11 and 13 may have the general configuration of target 9. Inside the focusing field and outside of the envelope 2 are placed vertical and horizontal deflecting coils, shown as a single unit 14, but it will be understood that these are two separate coils producing fields perpendicular to the beam 7 and to each other.

The cathode 4 may be connected to the negative 1,000 volt terminal of a power unit and the control grid to the cathode through a suitable negative bias source and an appropriate resist-

2

ance 15. The anode 8 may be connected to the positive ground terminal. The control screen 13 is connected so as to have a potential alternately negative and positive relative to shield screen 11 to control the escape of secondary electrons from the target.

The saw-tooth generator 16 is connected to the horizontal deflector coil of unit 14 to provide the varying electromagnetic field for horizontal scansion by beam 7. The vertical deflector coil of this unit is connected to a constant direct current voltage source to position the beam in the desired horizontal plane.

To record or store the signals of one scanning cycle on target 9 and discharge them in another cycle, I employ a polarity reverser, designated in general by reference character 17. This comprises a blocked type of multivibrator in which two tubes 18, 19, having plates and grids cross-coupled, are so biased that only one tube can be conducting at a time. Furthermore, the bias is such that when one tube is conducting and the other is not, the condition will be stable if no interference is present. However, if a sharp negative pulse is applied to the connection 20 common to the plates of the tubes, the condition of the two tubes will reverse; that is, the tube originally non-conducting then conducts and vice versa. Such a pulse is obtained by coupling the saw-tooth generator 16 to the grid of the input amplifier 21 through condenser 22 and connecting the plate of the amplifier to the lead 20 of the polarity reverser. When the pulse is produced, the voltage at both plates is lowered, due to the drop in resistance 23. If, for example, tube 19 be assumed as previously non-conducting, the condenser 24 will discharge down to the lowered voltage through the resistance 25 in the grid circuit of tube 18. Since the drop in this resistance is negatively applied, tube 18 blocks and tube 19 conducts. Upon occurrence of the next pulse, condenser 26 will discharge through resistance 27 and reverse the condition. Thus, upon production of one pulse by a positive peak of saw-tooth generator 16, the plate of tube 18 will be positive with respect to the plate of tube 19 and upon production of a pulse in the next cycle, the polarity will reverse.

A pentagrid tube 28 is used to impress the received signals on cathode beam 7. Accordingly, the first control grid of this tube is connected to the signal line 29 and the cathode is grounded through cathode bias resistor 30. The blocking condenser 31 connects the second control grid of this tube to the polarity reverser to shut off the

input signal to the storage tube during the reproducing cycle and turn it on during the recording cycle, as later explained in more detail.

The plate of tube 28 is connected to the positive terminal of a B supply source through resistance 32. The various other terminals of tubes 18, 19, 21 and 28 are connected to appropriate voltage terminals and need not be described. The plate terminal of tube 28 is coupled through condenser 33 to grid 6 of cathode beam tube 1.

The condenser 22 is connected through resistance 34 and negative bias source 35 to the cathode of tube 21, which is grounded. The high side of resistance 34 is connected to the grid of a blanking tube 36, which has its output circuit connected between the plate of tube 28 and ground. The grids of tubes 21 and 36 are biased by source 35 well below cut-off. The ground of tubes 18, 19, 21, 28 and 36 may be the minus terminal of the B source, or sources.

The plate of tube 18 is connected through condenser 37 and resistance 38 to ground and the high end of resistance 38 is connected to control screen 13.

Suppose the saw-tooth generator 16 makes tube 19 of the polarity reverser 17 non-conducting as it causes the beam 7 to sweep across the target 9. The potential at the plate of tube 19 rises and turns on amplifier 28. The signals coming in over line 29 modulate the beam 7. Simultaneously with the reversal of polarity, the voltage of screen 13 becomes negative by virtue of its coupling to the plate of the conducting tube 18 through the large condenser 37 in conjunction with the high resistance 38. Thus, as the beam 7 sweeps across the target in this cycle, the secondary electrons bombarded from the target pass through screen 11 but are driven back therethrough and to the target because of the relative negative potential of screen 13. Due to the focusing action of the axial field of coil 3, these return substantially to the spots from which they were emitted. The electrons landed from the beam thus drive the scanned line of the dielectric surface varyingly negative in accordance with the signal. On the next cycle of the saw-tooth generator, tube 18 blocks and tube 19 conducts. This blocks tube 28 and prevents the signals from modulating beam 7. The rise of potential at the plate of tube 18 raises the potential of control screen 13 above the potential of shield screen 11, which is above the potentials of dielectric target 9, and the secondary electrons bombarded therefrom by the beam are drawn through both screens 11 and 13 and are collected by anode wall 8a.

The electron velocity of the beam is such that the ratio of emission of secondary electrons to primary electrons is greater than unity; that is, more electrons leave the bombarded element of the target than are landed from the beam. Hence, the elemental areas become positive. The copious emission of secondary electrons is such that this scansion of the beam raises all of the scanned areas of the target up to the potential of shield screen 11, as no secondary electrons can pass through the shield screen should the target element under bombardment become more positive than the shield screen. This action of the beam in the second scansion causes displacement currents to flow in the elemental condensers formed by the surface of the dielectric under bombardment and the signal plate. These currents flowing through the output resistor 40 produce potential changes in succession on the sig-

nal plate 10 proportional to the difference in potential between those of the elemental areas produced by the first scansion of the beam and the relatively positive uniform potentials produced by the second scansion. These varying potentials on the plate 10 may be utilized in any desired way through conductor 39, such as a synchronously operating oscilloscope.

The invention is not limited to putting signals on the plate in alternate scancions of the beam, as the use of suitable known counting devices may provide other scoring procedure and various other modifications may be made without departing from the scope of the invention.

Having described my invention, what I claim is:

1. A signal storage system comprising a cathode beam tube having a gun, a signal plate having a dielectric target surface facing said gun, a screen having one of its sides adjacent to and facing said dielectric target surface, and a second screen adjacent to and facing the other side of the first screen, means for scanning the beam of said gun over said surface through said screen, a potential source for making the first screen positive in respect to the cathode of said gun and a source of alternating potential for making the second screen positive in respect to the first screen in one scansion of the beam over said surface and negative thereto in another scansion thereof.

2. A signal storage system comprising a cathode beam tube having a gun, a dielectric target positioned with one of its sides facing said gun, a screen having one of its sides adjacent to and facing said side of the target, and a second screen adjacent to and facing the other side of the first screen, means for making the first screen positive in respect to the cathode, means for scanning the cathode beam over said target, said beam having sufficient electron velocity to produce secondary electrons from the target whose ratio to primary electrons is greater than unity and a source of alternating potential for making the second screen positive in respect to the first screen in one scansion of the beam over said target and negative thereto in another scansion.

3. A signal storage system comprising a cathode beam tube having a gun, and a dielectric target positioned with one side facing the gun, means for scanning a modulated beam over said target with sufficient electron velocity to produce secondary electrons from the target whose ratio to primary electrons is greater than unity and a control electrode in said tube and a source of alternating potential applied to said electrode to cause it to attract secondary electrons from the target during one scansion of the beam thereover and to repel them back to the target in another scansion thereof.

4. A signal storage system comprising a cathode beam tube having a gun, a dielectric target positioned with one of its sides facing the gun, and a screen having one of its sides adjacent to and facing said side of the target, means for scanning a modulated beam over said target through said screen with sufficient electron velocity to produce secondary electrons from the target whose ratio to primary electrons is greater than unity and a source of alternating potential connected to said screen to cause it to attract secondary electrons from the target in alternate scancions of the beam.

5. A signal storage system comprising a cathode beam tube having a gun, a dielectric target positioned with one of its sides facing the gun, a screen having one of its sides adjacent to and

facing said side of the target, a signal plate on the other side of the target, means for scanning a modulated beam over said target through said screen with sufficient electron velocity to produce greater than unity electron emission from the target and a source of alternating potential connected between said screen and said signal plate to attract emitted electrons from the target during one scansion of the beam and to repel electrons back to the target in another scansion thereof.

6. A signal storage system comprising a cathode beam tube having a gun, a dielectric target positioned with one of its sides facing the gun, a screen having one of its sides adjacent to and facing the other side of the target, a second screen adjacent to and facing the other side of the first screen, a signal plate on the other side of the target, means for making the first screen positive in relation to the cathode of said gun, a saw tooth generator, means connected to said saw tooth generator for scanning the cathode beam over said target through said screens said beam having sufficient electron velocity to produce electron emission from said target greater than unity and a multivibrator controlled by said saw tooth generator for making the second screen alternatively positive and negative in respect to the first screen at alternate scancions of said beam over the target.
